(57) **CLAIM**

The ornamental design for an implant release handle, as shown and described.

DESCRIPTION

FIG. 1 is a perspective view of the implant release handle showing the new design;

FIG. 2 is a top view of FIG. 1;

FIG. 3 is a right profile view of FIG. 1;

FIG. 4 is a left profile view of FIG. 1;

FIG. 5 is a front view of FIG. 1;

FIG. 6 is a rear view of FIG. 1;

FIG. 7 is a bottom view of FIG. 1;

FIG. 8 is a perspective view of another embodiment of an implant release handle showing the new design;

FIG. 9 is a top view of FIG. 8;

FIG. 10 is a right profile view FIG. 8;

FIG. 11 is a left profile view FIG. 8;

FIG. 12 is a front view of FIG. 8;

FIG. 13 is a rear view of FIG. 8; and,

FIG. 14 is a bottom view of FIG. 8.

The broken lines in these drawings illustrate environmental features only and form no part of the claimed design. The shade lines shown represent surface shading and not surface ornamentation, color, or material type. Where different types of surface shading are employed, they represent a surface contrast.
